(57) **CLAIM**

The ornamental design for a water dispenser and bottle, as shown and described.

DESCRIPTION

FIG. 1 is a front perspective view of a water dispenser and bottle showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof;

FIG. 7 is a bottom plan view thereof;

FIG. 8 is an enlarged perspective view of the bottle portion of the water dispenser and bottle with the dispenser portion removed for ease of illustration;

FIG. 9 is a front elevational view thereof;

FIG. 10 is a top plan view thereof; and,

FIG. 11 is a bottom plan view thereof.
